TOWEL RACK

Genevieve E. Doucet, 122 N. O'Connell Ave.,
Springfield, Minn.

Filed Oct. 24, 1960, Ser. No. 62,581

Term of patent 7 years

(Cl. D4—3)

FIG. 1

FIG. 2

FIG. 3

FIG. 4

FIG. 1 is a view in perspective of a towel rack showing my new design;

FIG. 2 is a front elevational view thereof, the rear being substantially plain;

FIG. 3 is a top plan view thereof; and

FIG. 4 is an elevational view taken from the left end thereof, the right end being a mirror image of said left end.

I claim:

The ornamental design for a towel rack, as shown and described.
